WINDOW WITH SLIDING PANES

Farr Nutter, Winchester, Va.

Application April 3, 1947, Serial No. 739,139

10 Claims. (Cl. 20—56.2)

1

This invention relates to an improvement in windows and pertains particularly to window construction in which a pane of glass or the equivalent is slidable vertically and is frictionally held so as to be adjustable to any predetermined position.

Heretofore various arrangements have been provided for adjusting windows vertically. The conventional double hung window is an example of a slidable sash which carries panes of glass. Glass panes have also heretofore been mounted for sliding movement laterally within a fixed frame, thus in contrast to a slidable sash. It has also been proposed to provide for the vertical adjustment of glass panes which are held by metal spring devices adapted to engage the lateral edges of the panes. This latter form of construction has faults by reason of the engagement of metal with glass, a combination which is both noisy and destructive to both the metal and the glass. Such an arrangement is peculiarly damaging to the edges of laminated glass panes and is entirely unsuitable when a double or vacuum-type of pane is used. The present invention is a departure from the above mentioned constructions and avoids the structural troubles, wear and tear and noise inherent to that type of pane mounting in which the pane is frictionally held by a metal spring in engagement with the edge of the pane.

One of the features of the present invention is the use of a portion of the window sash to serve as an adjustable clamping strip whereby pressure is brought against the face of the pane adjacent its marginal edge. This construction makes it possible for the window sash to have the appearance and general contour of a conventional sash; however, the clamping strip portion which extends vertically is adjustable with respect to the main portion of the sash and with respect to the pane against which it is adapted to exert pressure.

This improved construction also provides an advantage by reason of the fact that the pressure is exerted against the face of the pane as contrasted to the edge of it. Obviously the pane should be smooth, whereas quite frequently the edges of glass panes are not dressed down to very exact smoothness. Thus the application of retaining pressure against a smooth surface reduces to a minimum both wear and tear and makes it possible for the pane to be adjusted vertically freely and evenly.

In conjunction with the adjustable vertical strip to assist in holding the slidable pane, the

construction also includes the use of a felt or cloth friction strip to embrace the lateral marginal edges of the slidable glass pane. The sash is provided with opposed grooves in which the pane is adapted to slide vertically. Preferably the grooves extend the height of two panes and the upper pane may be fixed. The friction strip is located in the grooves and is adapted to fit in between the edge of the glass pane and the walls of the groove, thus extending slightly along one face of the pane, around the edge thereof, and slightly along the opposite face of the pane. Thus the strip has substantially a U-contour although the U is in a horizontal direction inasmuch as the strip extends vertically. The adjustable clamping strip may be either a muntin or one inner front face of the side rail of the sash.

The foregoing and additional details and advantages of the construction will be described and claimed in the following specification and claims and are illustrated in the accompanying drawings, in which:

Fig. 1 is an elevational view of the face of a window sash four panes in height and of which the bottom panes and the panes next to the top are slidably mounted;

Fig. 2 is a sectional view taken on the line 2—2 of Fig. 1 looking in the direction of the arrows;

Fig. 3 is a sectional view taken on the line 3—3 of Fig. 1, looking in the direction of the arrows;

Fig. 4 is an enlarged fragmentary sectional view taken on the line 4—4 of Fig. 1; and

Fig. 5 is an enlarged horizontal sectional view of one form of the structure, broken away at the center, showing the front or inner face of a window sash used as the strip for clamping the slidable pane.

Referring in detail to the several figures of the drawings, like reference characters identify like structural parts.

As explained in the foregoing, this improvement relates to a window construction in which a pane of glass or the equivalent is slidably mounted vertically, and means are provided for frictionally holding it in any adjusted position by pressure against the face of the pane. Such a construction might be installed in a sash or framework in which the slidable pane constitutes the only transparency or closure for a ventilating opening. However, in its most obvious use, the construction is peculiarly adapted to a window sash at least two panes high. With this characteristic construction as a criterion, Fig. 1 illustrates a

window sash four panes high, in which the lowermost pane and the pane third from the bottom are slidably mounted. According to Fig. 1, the right hand side rail is indicated at 1, and 2 is the left hand side rail of the sash. 3 is the top rail and 4 is the bottom rail. Those rails may be secured together in any convenient manner sufficient to provide the inherent strength essential for a window sash or door. 5 is a conventional meeting rail which serves to strengthen the sash framework formed by the rails 1, 2, 3 and 4. The meeting rail 5 also serves to limit the lower movement of the panes next above it and to separate those movable panes from the fixed panes next beneath the rail 5.

Cross bars 6 are shown at the bottom of the fixed panes and at the top of the slidable panes, as will be explained. 7 indicates the vertical muntins, two of which extend from the top rail 3 to the lower rail 4 and are spaced to divide the window sash into an arrangement three panes wide. The window sash construction, wherein the main portion of the muntins 7 cross the meeting rail 5, or are otherwise joined to it and any portion of the cross bars 6 does not form any essential part of this improvement. Such structural features are not illustrated in the drawings. Rather, the drawings are directed to the construction which makes the use of slidable panes feasible and provides adjustable means for controlling the pressure against each slidable pane.

Referring to the panes, 8 indicates fixed panes at the top of the sash. 9 are the slidable panes. This grouping is duplicated above and below the center meeting rail 5. Hand grip lifting pieces 10 are shown on each of the slidable panes 9 and these gripping portions may be recesses, but preferably, because most window panes are relatively thin, the gripping elements 10 are provided by pieces of transparent or clear plastic secured to the face of the glass.

The framework of the sash is secured together at its corner portions by suitable nails or screws or other permanent or non-adjustable fastening means, indicated at 11.

Tensioning means for adjustably clamping a portion of the side rails so as to frictionally hold the slidable panes 9 in any vertically adjusted position is provided by screws 12 which are located in the face of the side rails 1 and 2 fairly closely adjacent the glazed portion of the sash, and preferably also located substantially in alignment with the cross bars 6 and the meeting rail 5. Similar adjusting screws 13 are indicated in the vertical muntins 7 midway of the height of the slidable panes. The manner of using the screws 12 and 13 to control the clamping pressure will be explained hereinafter.

Screws 14 are shown midway of the height of the fixed panes 8 to insure adequate strength and provide further adjustability for the muntins relative to the panes 9 when they are in the upper position.

With reference to Figs. 2-5 inclusive, it will be noted that the side rails 1 and 2 are formed of two vertical strips and that the strip facing inwardly is indicated at 1 and 2, whereas the outer strip is indicated at 15. It will also be obvious that the panes are mounted in grooves located chiefly within the thickness of the rail portion 15. The main strength of the sash is supplied by the rail portions 15 and the cross rails at top and bottom 3 and 4, which are tenoned to the side rail portions as indicated at 16 (Fig. 2). The adjacent faces of the side rail portions 15 are

provided with two grooves 18. In one of these sets of grooves is mounted the fixed pane 8. The second groove, located inwardly of the groove for the fixed pane, is more correctly a substantially right angled notch in the edge portion of the rail portion 15. The adjacent face of the side rail portions 1 and 2 completes the side walls of this second groove, as will be obvious by reference to Figs. 3 and 5.

Resilient friction means for engaging the marginal edge portions of the slidable glass panes 9 is provided by use of a felt strip extending lengthwise the length of the groove and embracing the edge portions of the glass. Thus the glass pane is seated in a strip of felt or cloth 19, which extends in the shape of a U laterally around the edge of the side edges of the glass and substantially fills the space of the groove between the glass and the walls of the groove 18. The packing means between the fixed pane 8 and the walls 18 of its groove may also be of felt but preferably the outside portion exposed to the weather should be of weather resisting material such as putty or cement.

Adjustment of the tension, pressure, on the slidable panes 9 is effected in the following manner and by reason of the peculiar construction now to be described. Clamping pressure along that face of the glass panes 9 next adjacent the side rails 1 and 2 is provided by the release or tightening of the screws 12. Those screws, as will be evident from inspection of Figs. 3 and 5, pass through the side rail strips 1 and 2 into the heavier portions 15 of the side rails. In short, the strips 1 and 2 are chiefly inner facing strips. To provide for the necessary movement of the strips 1 and 2 with respect to the portions 15, it is necessary that there be space provided between the strips 1 and 2 and the rails 15 lengthwise of those strips and adjacent the window spaces. That space between the strips should increase from zero at the outer margins of the sash to the window opening, substantially as indicated in Figs. 3 and 5. Such a construction makes it possible to regulate, by means of the screws 12, the distance between the strips 1 and 2 and the rail portions 15 in the region adjacent the window openings. Thus the faces of the strips 1 and 2 adjacent the window openings are brought to bear against the felt strip which embraces the marginal edge portions of the face of the panes 9 and the clamping action of the strips 1 and 2 against the panes and the felt 19 is regulated. Thus, also, the sliding vertical positioning of the panes 9 may be controlled.

In lieu of the bevelling of the adjacent face of the strips 1 and 2 with respect to the adjacent face of the rails 15, a somewhat similar effect may be obtained by making certain that the felt strip 19 for the panes 9 projects inwardly beyond the face of the rail portions 15. However, it will be obvious that the rails 1 and 2 should preferably give the appearance of a conventional window sash except for the use of the adjusting screws 12 and 13, and for this reason the thickness of the felt around the edges of the panes 9 should not be excessive or so great as to throw the strips 1 and 2 out of correct position.

Adjustment of the screws 13 serves to regulate the tension applied through the vertical muntins which thus control the clamping effect on the center portions of a sash three or more panes in width. In Figs. 3 and 4, it will be obvious that adjustment of the screws 13 will regulate the positioning of the inner muntin strips 7 with respect

to the muntin core 7^a and its outer facing strip 17. The outer facing strip 17 is conventional and may be used to assist in the weatherproofing and exterior finish of the sash.

In Fig. 2, there is illustrated a suitable form of construction for the meeting rail, the inner decorative strip of which is indicated at 5. The heavier portion of the meeting rail is indicated at 5^a, and 5^a receives the upper edge portion of the fixed pane 8 and also receives the upper slideable pane 9 when it is in the lowered position.

Also in Fig. 2 is illustrated, in cross section, a suitable construction for the cross bar which has an inner facing strip 6 and an intermediate or outer portion 6^a, which fills the space between the fixed pane 8 and the slideable pane 9 and likewise may support the lower end of the fixed pane 8. However, inasmuch as the fixed pane 8 is preferably fixedly secured, it may be held in place solely by putty.

It will be obvious that the grooves for the reception of the slideable pane 9 should be substantially double the length of the pane whereby a track is provided for the slideable adjustment of the pane.

From the foregoing, it will be clear that this improvement provides a construction whereby a pane of glass or its equivalent, free from any binding strip or protective edge carried by the pane, is mounted for vertical adjustment and that the regulation of the pressure at the marginal faces of the pane may be performed by adjustment of vertical strips which have the appearance of being an inherent and normal part of a conventional sash.

It will also be clear that the adjusting means, namely, the screws 12, 13 and 14 are readily accessible at the face of the window and are not obscured.

It will be understood from the foregoing that the window sash described has side edges and opposed faces which latter have directly visible display portions, characteristic of conventional window sash, and in which the adjustable tensioning screws are located, as indicated at 12, 13 and 14.

I claim:

1. In a window at least two panes in height, an upper pane, a lower pane, securing means adjustable horizontally engaging the face of said lower pane adjacent a lateral edge thereof to hold said lower pane at any predetermined height, the lower pane being slideable vertically with respect to the upper pane and with respect to the lateral securing means, a sash common to both of said panes and having opposite faces constituting display portions, a fixed cross bar rigidly mounted opposite the lower end of said upper pane and in engagement therewith to support the same and which cross bar is opposite the upper end of said lower pane when the latter is in the lowered position, said lower pane having both faces parallel throughout and the lateral marginal portions of said parallel faces being in contact with said securing means, and means for regulating the pressure of said securing means against the face of said lower pane, said regulating means being on the display portion of the sash and directly accessible at the face of the sash for convenient adjustment.

2. In a window at least two panes in height, 70 a sash common to both of said panes and having opposite faces constituting display portions, one of said panes being stationary and held against vertical adjustment, and the second of said panes being slideably mounted within said sash and in

a plane parallel to said first pane and spaced therefrom, and securing means adjustable horizontally for holding said second pane in any position vertically comprising a non-metallic U-shaped resilient binding strip carried by said sash and embracing the lateral edges of said second pane and having a portion in contact with the opposite faces of said second pane adjacent the edges thereof, and a vertically extending portion of said sash constituting a clamping strip in engagement with said resilient binding strip, and means for adjustably tensioning said vertical clamping strip with respect to said binding strip and said second pane, said tensioning means being on the display portion of the sash and directly accessible at the face of the sash for convenient adjustment.

3. In a window at least two panes in height, a sash common to both of said panes and having opposite faces constituting display portions, the upper pane being fixed and the lower pane being slideable vertically, and clamping means for securing said lower pane in any predetermined position vertically comprising a vertical strip consisting of a portion of the sash and which strip is adapted to exert pressure against one face of said second pane and is adjustably mounted with respect to the remaining portion of the sash and with respect to said lower pane so as to regulate the pressure by said strip against said lower pane, said vertical strip being on the display portion of the sash and directly accessible at the face of the sash for convenient adjustment.

4. In a window at least two panes in height, 35 a sash common to both of said panes and having vertical framing at opposite edges of the panes thereof and having opposite faces constituting display portions, one of said panes being fixed against vertical movement, said sash having opposed grooves in the vertical framing thereof and extending a distance equivalent to the height of both of said panes, a second pane adjustably and slideably mounted in said opposed grooves, and adjustable clamping means carried by said sash and adjustable with respect to said second pane, and toward and from said second pane at right angles to the plane of said second pane, whereby the pane is clamped thereby and may be frictionally held in any desired position vertically in said opposed grooves, said clamping means being on the display portion of the sash and directly accessible at the face of the sash for convenient adjustment.

5. In a window at least two panes in height, 55 a sash common to both of said panes and having vertical framing at opposite edges of the panes thereof and having opposite faces constituting display portions, one of said panes being fixed against vertical movement, said sash having opposed grooves in the vertical framing thereof and extending a distance equivalent to the height of both of said panes, a second pane adjustably and slideably mounted in said opposed grooves, and adjustable clamping means carried by said sash and movable with respect to said second pane, and toward and from said second pane at right angles to the plane of said second pane, whereby the pane is clamped thereby and may be frictionally held in any desired position in said opposed grooves, said clamping means comprising a vertical muntin strip, said clamping means being on the display portion of the sash and directly accessible at the face of the sash for convenient adjustment.

6. In a window at least two panes in height,

a sash common to both of said panes and having a main fixed portion and a second portion adjustable with respect to said main portion and having opposite faces constituting display portions, the upper of said panes being fixed and the lower of said panes being slidable vertically, and clamping means for securing said lower pane in any predetermined position comprising a vertical strip consisting of said second portion of the sash and which strip is adapted to adjustably exert pressure against one face of said lower pane and is adjustably mounted with respect to the main portion of the sash, and a fixed cross bar rigidly mounted opposite the lower end of said first pane and in engagement therewith to support the same, which cross bar has a slot vertically therethrough in spaced relation from said first pane and through which slot said second pane may be slidably adjusted, said vertical strip being on the display portion of the sash and directly accessible at the face of the sash for convenient adjustment.

7. In a window at least two panes in height, a sash common to both of said panes and having a main fixed portion and a second portion adjustable with respect to said main portion and having opposite faces constituting display portions, the upper of said panes being fixed and the lower pane being slidable vertically, clamping means for securing said lower pane in any predetermined position comprising a vertical strip consisting of said second portion of the sash and which strip is adapted to adjustably exert pressure against one face of said lower pane and is adjustably mounted with respect to the main portion of the sash, and grip means supported by said slidable lower pane whereby the pane may be lifted by hand, said vertical strip being on the display portion of the sash and directly accessible at the face of the sash for convenient adjustment.

8. In a window at least two panes in height, a sash common to both of said panes and having opposite faces constituting display portions, the upper pane being fixed and the lower pane being slidable vertically, clamping means for securing said lower pane in any predetermined position comprising a vertical strip consisting of a portion of the sash and which strip is adapted to exert pressure against one face of said second pane and is adjustably mounted with respect to the remaining portion of the sash.

and with respect to said lower pane, and grip means secured to said lower slidable pane and projecting from the surface of said pane on the opposite side thereof from said fixed pane whereby said slidable pane may be lifted by hand, said vertical strip being on the display portion of the sash and directly accessible at the face of the sash for convenient adjustment.

9. In a window sash having opposite faces constituting display portions, a pane mounted in said sash for slidable adjustment, and clamping means for securing said pane in any predetermined vertical position comprising a vertical strip consisting of a portion of the sash and which strip is adapted to apply pressure against said pane at right angles to the face thereof and is adjustably mounted with respect to the remaining portion of the sash and with respect to said pane, said vertical strip being on the display portion of the sash and directly accessible at the face of the sash for convenient adjustment.

10. In a window construction, a sash having opposite faces constituting display portions, a pane mounted in said sash for slidable adjustment, and grip means supported by said slidable lower pane whereby the pane may be lifted by hand, said vertical strip being on the display portion of the sash and directly accessible at the face of the sash for convenient adjustment.
